(57) **CLAIM**

The ornamental design for a spray gun nozzle, as shown and described.

DESCRIPTION

FIG. 1 is a rear perspective view of the spray gun nozzle according to the invention;

FIG. 2 is a left side view of the spray gun nozzle;

FIG. 3 is a right side view of the spray gun nozzle;

FIG. 4 is a rear view of the spray gun nozzle;

FIG. 5 is a front view of the spray gun nozzle;

FIG. 6 is a top view of the spray gun nozzle; and,

FIG. 7 is a bottom view of the spray gun nozzle.

The broken line showing of a spray gun and container is for illustrative purposes only and forms no part of the claimed design.
